(57) **CLAIM**

The ornamental design for a storage bin for aircraft, as shown and described.

DESCRIPTION

FIG. 1 is a bottom perspective view of the present invention; FIG. 2 is a front elevational view of the present invention shown in FIG. 1;

FIG. 3 is a rear elevational view of the present invention shown in FIG. 1;

FIG. 4 is a right side elevational view of the present invention shown in FIG. 1, the left side elevational view being a mirror image thereof;

FIG. 5 is a top plan view of the present invention shown in FIG. 1;

FIG. 6 is a bottom plan view of the present invention shown in FIG. 1;

FIG. 7 is a bottom perspective view of a second embodiment of the present invention;

FIG. 8 is a front elevational view of the present invention shown in FIG. 7;

FIG. 9 is a rear elevational view of the present invention shown in FIG. 7;

FIG. 10 is a right side elevational view of the present invention shown in FIG. 7, the left side elevational view being a mirror image thereof;

FIG. 11 is a top plan view of the present invention shown in FIG. 7; and,

FIG. 12 is a bottom plan view of the present invention shown in FIG. 7.

In the drawings the broken lines depict environmental subject matter only and form no part of the claimed design.

1 Claim, 12 Drawing Sheets

Related U.S. Application Data

is a continuation of application No. 14/179,494, filed on Feb. 12, 2014, now Pat. No. 8,955,805, which is a continuation-in-part of application No. 13/765,652, filed on Feb. 12, 2013, now Pat. No. 9,162,617.
